Patented June 8, 1965

201,292

SILVERWARE BASKET

Robert D. Mundt, Jefferson County, Ky., assignor to General Electric Company, a corporation of New York

Filed Sept. 28, 1964, Ser. No. 81,894

Term of patent 14 years

(Cl. D44—29)

FIG. 1

FIG.2

FIG.3

FIGURE 1 is a perspective view of a silverware basket embodying my new design;

FIGURE 2 is a bottom plan view thereof, on a slightly reduced scale; and

FIGURE 3 is a partial cross-sectional view taken on the line 3—3 of FIGURE 2 in the direction of the arrows.

The essential features of the design are shown in full lines in the drawings.

I claim:

The ornamental design for a silverware basket, substantially as shown and described.
